PLATE OR SIMILAR ARTICLE

Bjørn Wiinblad, Kongens Lyngby, Hjortekaer, Denmark, assignor to Rosenthal-Porzellan Aktiengesellschaft,
Selb, Bavaria, Germany, a corporation of Germany

Filed Oct. 13, 1964, Ser. No. 82,162

Claims priority, application Germany Apr. 25, 1964

Term of patent 14 years

(Cl. D44—15)

FIG. 1.FIG. 2.FIG. 3.FIG. 1 is a top plan view of a plate or similar article showing my new design, it being understood that the ornamentation shown within the dashed line sector is continued about the entire surface of the plate, in the path indicated;

FIG. 2 is an enlarged scale sectional view taken on line 2—2 of FIG. 1; and

FIG. 3 is an enlarged scale sectional view taken on line 3—3 of FIG. 1.

I claim:

The ornamental design for a plate or similar article, as shown and described.
